FIG. 1

To all whom it may concern:

Be it known that I, Madaleine B. Sunkees, a citizen of the United States, residing at Los Angeles, California, have invented a new, original, and ornamental Design for a Glove or Similar Article, of which the following is a specification, reference being had to the accompanying drawing, forming a part thereof.

In the drawing:

Fig. 1 is a rear view of a glove, showing my new design; and

Fig. 2 is a side elevation thereof.

The essential features of my design reside in the portions shown in solid lines on the drawing. The two chain type portions of the ornamentation on the cuff extend completely around the cuff section—the remainder of the cuff ornamentation does not.

I claim:

The ornamental design for a glove or similar article, as shown and described.
